UNITED STATES PATENT OFFICE.

JOSEPH A. REVILL, OF FLORENCE, SOUTH CAROLINA.

STEAM-HEATED SADIRON.

Application filed October 21, 1926. Serial No. 143,095.

My invention consists of certain improvements in sad irons, and relates especially to such an iron equipped with means of heating by steam from any desirable and available source.

The object of my invention is to produce a simple, inexpensive and efficient device of this character, having as an advantageous feature simple means of heating by steam, as will appear from further description of the device and especially pointed out in the claim.

In the accompanying drawing, forming a part of this application, in which like characters represent like parts, Figure 1 represents a top plan view of an iron embodying my invention; Figure 2 is a longitudinal vertical section of same; and Figure 3 represents a front plan view of a metal block, fitted with spring pressed steam valves and steam pipes, to be fastened to a table or stand, and through which the steam passes from the source to the iron, and from the iron to the discharge pipe.

1 represents a metal sad iron having a hollow steam chamber 2 therein, intermediate between the top 3 and bottom 4 of the iron.

The iron is fitted at the back end with two spring pressed steam valves, 5 5, screwed 30 threaded into the body of the iron 1. Each of these valves is composed of an outer metal tube 6 having the front end partly closed, with a small round hole 7 in the center of the end and a collar-like extension 8 extending out from, and being a part of the walls of the tube 6 over the opening 7, and with an inner metal tube 9 passing through a coil spring 10. The back end of the coil spring 10 rests against the back wall 11 of the iron.

40 A metal ball 12 is placed between the front end of the coil spring 10 and the opening in the end of the outer tube 6, closing the opening 7 when resting against it. Through the right hand valve 5 the steam passes into the steam chamber 2, and the left hand valve 5 serves as an outlet for the steam passing from the steam chamber 2 to the discharge valve.

At the top of the iron is an ordinary handle 50 consisting of a wooden hand-clasp 13, of any desired shape or form, through which passes a metal rod 14, bent to fit and fastened to the body of the iron 1 by means of two screw-bolts, 15 15, which construction is common in art.

The metal block 16, shown in Figure 3 of

the plan or drawing, is likewise fitted with two steam pressed valves, 5' 5', identical in construction with those in the body of the iron 1, the right hand valve 5' being used to admit the passage of steam from the steam supply pipe 17 into the right hand inlet valve 5 of the body of the iron, 1, and thence into the steam chamber 2; while the left hand valve 5' is used to admit the passage of steam from the left hand outlet valve of the body of the iron 1 to the steam discharge pipe 18; each of the valves being so constructed that when the iron 1, is placed against the block 16, the metal balls 12' and 12' in the block press against the balls 12, 12 in the valves in the iron, the ball 12 also pressing against the coil spring 10, and ball 12' pressing against coil spring 10', thus automatically opening the valves 5' 5' and 5 5, allowing steam to pass into and out of the steam chamber 2; and when the iron 1 is removed from against the block 16 all valves 5 5 and 5' 5' automatically close.

The steam supply pipe 17 is connected with any suitable source of steam supply, such as boilers used for heating other laundry equipment or appliances, and common to the art; while the steam discharge pipe 18 may be extended to any desired point of discharge.

From the bottom and front of the metal block 16, extends a flat sheet-metal plate 19, upon which the iron 1 rests while being heated. At the front end of this sheet-metal plate 19 is fastened a small grooved wheel 20, by means of a screw-bolt 21 and nut 22, passing through the wheel 20 and a metal frame 23. The point of the body of the iron 1 rests against the groove in the wheel 20, thus causing the iron 1 to press firmly and evenly against the block 16 while being heated.

At the front end of the metal block 16, and at the back of the valves 5' 5', in the block, is placed two metal plugs 24 24, screw-threaded into the opening in the block 16, through which the valves 5' 5' were placed and fitted, serving as a closing for such openings. To the front of each of these metal plugs 24 24 is a small chamber 25 25, containing a coil spring 26 26 upon which the valves 5' 5' rest, and forming an opening through which steam passes from the steam supply pipe 17 to the inlet steam valve 5' in the block to the steam discharge pipe 18.

The metal block 16 is fastened to any suitable stand or table, by means of a screw bolt 27, and is held firmly to the table or stand by means of a coil spring 28, such means and construction being common in art, and not necessarily the manner of fastening the block 16 to a table or stand, but is such manner of fastening the block 16 to a table or stand as I have shown in the accompanying plan or drawing.

From the foregoing it is evident that I have provided a convenient, simple and efficient means whereby a sad iron may be heated with steam and after being thus heated 15 may be disconnected entirely from the source of steam supply while being used.

Having thus described my invention what I claim and desire to secure by Letters Patent, is:

A device for supplying steam to an iron of 20 a type having a hollow steam chamber and provided with inlet and outlet openings through a wall thereof and spring pressed 25 valves projecting through said openings, comprising a plate having a block with inlet and outlet passages mounted on one end thereof, said passages being provided with like valves, means for supplying steam to said block and means at the other end of the plate for positioning the iron whereby the 30 valves therein may contact with the valves in the block to open all of said valves and allow the steam to pass into and out of the steam chamber.

In testimony whereof I hereunto affix my 35 signature.

JOSEPH A. REVILL.
